CLAIM

The ornamental design for a chair base having wood legs, as shown and described.

DESCRIPTION

FIG. 1 is a perspective view of a chair base having wood legs of the invention, where the wood legs extend below top caps.

FIG. 2 is a front side view of the chair base of FIG. 1.

FIG. 3 is a back side view of the chair base of FIG. 1.

FIG. 4 is a left side view of the chair base of FIG. 1.

FIG. 5 is a right side view of the chair base of FIG. 1.

FIG. 6 is a top view of the chair base of FIG. 1.

FIG. 7 is a bottom view of the chair base of FIG. 1.

FIG. 8 is a perspective view of a second embodiment chair base having wood legs, where wood line shading of the legs is shown to identify the wood legs extending below the top caps. The front, back, left, right, top, and bottom views of the second embodiment are identical to those shown in FIGS. 2 through 7 except with the wood appearance of the legs shown with wood line shading as shown in FIG. 8 applied; and,

FIG. 9 is a right side view of the chair base of FIG. 1, a seat shown in broken lines, and a human person shown sitting on the seat.

The broken lines of the chair base of FIGS. 1 through 9 are for the purpose of illustrating unclaimed portions of the chair base and form no part of the claimed design. The portions of the human person and the seat in FIG. 9 are not part of the claimed design.
